TETHERED PROJECTILE GAME

Edmund C. Talbot, Fall River, Mass.

Substituted for abandoned application Serial No.
555,101, September 21, 1944. This application
September 10, 1948, Serial No. 48,660

1 Claim. (Cl. 273—40)

1

This application is a substitute for abandoned application No. 555,101, filed Sept. 21, 1944.

My invention relates to games of the tethered projectile type and is especially adapted for employment in a game simulating bowling, although it will be understood that is in no wise limited to such use.

Briefly and generally stated, the invention has among its objects the provision of a game, as characterized, which provides a playing portion for each of two players, there being a separate tethered projectile associated with each playing portion, and both of said tethered projectiles being preferably carried by a single supporting member.

Additionally, the invention contemplates a game of the kind stated which incorporates novel receptacle-providing back-stop means for game elements to be actuated by the tethered projectile, the nature of the arrangement of the various parts being such that they can be readily assembled for use and packed away when desired.

Various other objects and advantages of the invention will be apparent from a reading of the following description of the preferred embodiment of my inventive concept which is illustrated in the accompanying drawing.

In the drawing:

Figure 1 is a perspective view of a game embodying my invention and disclosing two separate playing surfaces opposite one another;

Fig. 2 is a fragmentary longitudinal section through the game board or base member of Fig. 1;

Fig. 3 is a perspective view of one of the game elements adapted to be acted upon by the tethered projectile.

Referring to the drawing by reference characters, numeral 5 designates a rectangular base having the side walls 6 which are secured to the base by staples or the like 1, or in any other preferred manner. As illustrated, the side walls 6 preferably increase in height from each end of the base 5 to an apex 6a approximately midway the length of base 5. The object of increasing the height of the walls 6 in the direction of the mid-point of the base 5 is to provide confining flanges to prevent scattering of the game elements 9 beyond the sides of the base when they are struck by the projectile to be referred to herein-after.

In the illustrated form of the invention I have provided the usual triangularly arranged group of ten pin spots 8 adjacent each end of the base 5 with the apices pointed toward opposite ends of the base 5. Although the pins 9 may be of any

2

preferred form, I find it very desirable to use pins which embody enlarged bases 9a, and whose opposite end is pointed as shown. These pins may be, and preferably are, golf tees. The relatively enlarged bases 9a tend to maintain the pins in an upright position and greatly facilitate positioning the pins on the spots 8. Also, the enlarged base portions 9a of the pins 9 add to the interest of the game because such base portions tend to maintain upright a pin which is struck and shifted by another pin. This places a premium upon both thought and accuracy when next delivering the projectile 17 in an attempt to knock down said shifted pin and the other then standing pins.

In the game as illustrated, there being no pits into which pins 9 will be dropped as in a regular bowling game, I provide the boundary markers 10 which preferably take the form of transverse strips arranged rearwardly of each group of spots 8, and preferably raised above the upper surface of the base 5 as best indicated in Fig. 2. Staples, such as 11, or adhesive, or other means may be availed of for securing the transverse boundary strips 10 to the base 5.

Shifted pins which remain upright, or for that matter prone on the respective alley portions of base 5 in advance of the associated boundary marker 10 after delivery of the projectile 17 may be either removed or allowed to remain until the player has completed a "box," which constitutes three deliveries of projectile 17 as in the game of bowling. However, pins which have slid beyond the associated boundary marker 10 are considered as in the "pit" and out of play. Naturally, as heretofore pointed out, the leaving of shifted pins on the "alley" provides considerable of a problem for the player on the next delivery of the projectile 17. Obviously, the relatively large based pins greatly increase the interest in the game and draw heavily upon the skill of the player, for the reasons just advanced.

In order to reinforce the intermediate side wall portions 6, and also to provide a back stop rearwardly of the boundary marker 10 of each playing surface, I provide a transverse back stop panel 12 which is preferably slanted toward the adjacent end of the base 5 and has transversely turned terminal portions 12a secured by staples or the like 13 to the opposite side walls 6. It will be observed that the back stop panels or portions 12 cooperate to provide a hopper-like receptacle for the pins 9 when not in use, or for extra pins 9. By forwardly slanting the back stop panel members 12 they tend to prevent the pins 9 from "fly-

ing" by directing them downwardly towards the base 5.

In carrying out the invention, I provide, as illustrated in the drawing, a preferably rectangular (cross-section) post 14 whose lower end is snugly fitted into a similarly shaped hole 15' provided in the base 5, preferably midway between sides and ends of the latter. As best illustrated in Fig. 2, this post 14 provides a sustaining support for the intermediate lower edge portions of the back stop panels or members 12; and by so doing also, of course, reinforces the side walls 6 so that said side walls, and for that matter the back stop panels, may be made of cardboard or other light material. The post 14 rises a substantial distance above the base 5 and is provided with a transverse hole 14a through which extends the rod 15 whose opposite ends are transversely bored for the passage of the cords 16. The lower end of each cord 16 carries a ball or projectile element 17 to which reference has heretofore been made. The rod 15 may be removed from the hole 14a of the post 14, but preferably has a reasonably tight friction fit therein so that the portions of the rod which project from opposite sides of the post 14 will be of the same length. The length of each cord 16 and the length of each end of the rod 15 at opposite sides of the post 14, will preferably be approximately as illustrated in Fig. 1, so that it will be possible when delivering the projectile 17 to actually hit any individual one of the set of pins 9 even when they are rearwardly of the areas containing the spots 8.

From the foregoing description taken in connection with the accompanying drawing it is believed that the construction of my game will be readily apparent. Of course, the embodiment disclosed in the drawing is simply illustrative, and many changes and modifications can be made without departing from the spirit and scope of the invention as claimed hereinafter.

The game is played by delivering the projectile 17 from a point rearwardly of the end of the base 5. The projectile is not thrown, but is merely swung or allowed to drop. The score of the game may be kept the same as in the game of bowling. The provision of the boundary marker 10 to limit the playing area is not only of advantage for this purpose, but, being raised above the surface of base 5, it serves to effect the toppling of pins sliding thereagainst but still remaining upright.

Another feature of the game which may be availed of for scoring purposes is the cross-member 18 which is secured to post 14 and provides the hooks 18a which project beyond opposite sides of said post 14. After a player has completed one "box," which is to say, three swings

of the projectile 17, he may endeavor to make another score or count by so swinging his projectile as to cause the suspension cord thereof to engage itself in one of the hooks 18a.

Having thus described my invention, what I claim as new is:

A tethered projectile game comprising in combination, a substantially rectangular base, the top of said base providing two playing surfaces which extend inwardly from opposite ends of said base, a post extending upwardly from the center of said base between said playing surfaces, said post having its lower end fitted in a recess in said base, a cross bar frictionally engaged in an opening adjacent the upper end of said post and having its ends disposed above the respective playing surfaces, a tethered ball attached to each of the respective ends of the cross bar, game pieces positionable on the respective playing surfaces, all portions of each of said playing surfaces being in a path of possible travel of one of said tethered balls, side wall-providing pieces attached to the respective sides of the base, and defining the lateral limits of said playing surfaces, said side wall pieces increasing in height from the ends of the base to a point approximately midway the length of same, a transverse inner boundary defining strip for each playing surface, said strips mounted on the upper surface of the base and at opposite sides of said post, a pair of adjacent transversely disposed backstop providing panels extending above and across said base at opposite sides of said post and inclined away from the latter, said backstop panels having their ends transversely turned and secured to said opposite side wall pieces whereby to reinforce the same and provide a game piece receptacle between said backstop panels, and the middle lower edge portions of said backstop panels being braced against opposite sides of said post to reinforce the same and further reinforce said wall providing side pieces.

EDMUND C. TALBOT.
